[57] CLAIM

The ornamental design for a dispenser for rolled material, as shown and described.

DESCRIPTION

FIG. 1 is a top, front, and right side perspective view of a dispenser for rolled material showing my new design; FIG. 2 is a front elevational view thereof; FIG. 3 is a right side elevational view thereof, the left side elevation being a mirror image thereof; FIG. 4 is a top plan view thereof; FIG. 5 is a bottom plan view thereof; FIG. 6 is a rear elevational view thereof; and, FIG. 7 is a top, front, and left side elevational view thereof, the broken-line depiction of rolled material being for illustrative purposes only and forming no part of the claimed design.

FIG. 1

FIG. 2

FIG. 3

FIG. 4

FIG. 5

FIG. 6

FIG. 7
